UNITED STATES PATENT OFFICE.

WILLIAM A. SPARKS, OF ROCHESTER, NEW YORK.

DESIGN FOR A BURIAL-CASKET.

SPECIFICATION forming part of Design No. 18,172, dated March 6, 1888.

Application filed April 20, 1885. Serial No. 162,881. Term of patent 7 years.

To all whom it may concern:

Be it known that I, WILLIAM A. SPARKS, of the city of Rochester, in the county of Monroe and State of New York, have invented or produced a new and original Design for Burial-Caskets, of which the following is a description, reference being had to the drawings accompanying this application, in which—

Figure 1 is a plan view of a burial-casket showing my new design. Fig. 2 is a side elevation of the same. Fig. 3 is a cross-section of the cap or panel at the top of the casket.

My new design consists of a raised ridge on top of the casket, having concave sides and ends, as hereinafter described.

A indicates the casket, and B the lid. a is a raised ridge on top of the lid, the same being of angular form and carried up to a sharp edge. The sides are concave, as shown at b,

and the ends are also concave. One of these 20 ridges is used at each end of the lid, as shown. This ridge stands above the flat top of the lid and relieves the plainness of the top of the casket and presents an ornamental appearance.

Having described my new design, what I claim as new is—

The design for a burial-casket herein shown and described, consisting of a raised ridge on top of the lid angular in cross-section and concave at the sides and ends, as specified.

In witness whereof I have hereunto signed my name in the presence of two subscribing witnesses.

W. A. SPARKS.

Witnesses:

R. F. OSGOOD,
I. A. BAUM.
